UNITED STATES PATENT OFFICE.

CHRISTIAN W. FLINT, OF PORT TOWNSEND, WASHINGTON.

SUBMARINE LIFT-SAVING DEVICE.

1,117,826.

Specification of Letters Patent. Patented Nov. 17, 1914.

Application filed March 25, 1914. Serial No. 327,035.

To all whom it may concern:

Be it known that I, CHRISTIAN W. FLINT, a citizen of the United States, residing at Port Townsend, in the county of Jefferson and State of Washington, have invented certain new and useful Improvements in Submarine Life-Saving Devices, of which the following is a specification.

This invention relates to marine structures and especially to that class known as submarine boats.

The object of the invention is to provide means whereby the occupants of a sunken and disabled boat may be conveniently and safely transported to the water surface.

The invention consists, first, in the provision of a novel construction of a buoyant vessel which is adapted to accommodate the crew or passengers of a boat; secondly, in the provision of means whereby the people may be safely transferred from the boat into said vessel; third, in the devices for detachably connecting said vessel to the boat to enable the former being reliably cast off from the boat; and fourth, in various contrivances whereby the security of the vessel and boat are both safeguarded from becoming flooded from any cause appertaining to the vessel or in its employment.

The invention is illustrated in the accompanying drawings, in which—

Figure 1 is a vertical longitudinal section of a portion of a boat with my invention applied thereto. Fig. 2 is a similar fragmentary view of the same illustrating the vessel in released condition with respect to the boat. Fig. 3 is a horizontal section on line 3—3 of Fig. 2 with the packing gasket omitted. Fig. 4 is a vertical section on line 4—4 of Fig. 3.

Referring to said drawings the reference numeral 5 designates the deck of a submarine boat which is provided interiorly with walls 6 and a bottom wall 7 arranged to provide an inclosed space which is divided by a horizontal partition 9 to furnish a compartment 10 below the partition and a well 11 thereabove which is open at the top.

12 represents a man-hole in the partition 9 and an opening 13 is provided in one of the walls 6 to give access into the compartment 10. Provided for said opening is a door 14 which is arranged to be closed from the compartment to make a water-tight fit with the wall and is then secured by bolts

15 extending through the door and engaging in screw-threaded holes provided in the wall.

16 represents the main body of a vessel V having an extension 17 depending therefrom of less diameter than the vessel part 16 so as to extend into the well 11 and of a depth to terminate a short distance above the partition 9. The floor 18 of the extension 17 is provided with a man-hole 19. Riveted or otherwise rigidly secured to the opposing faces of the partition 9 and floor 18 respectively, are frame elements 20 and 21 with an interposed gasket 22 of rubber or other suitable packing material.

23 represents cap screws extending through holes provided in the floor 18 and the frame element 21 to engage in threaded holes 24 provided therefor in the frame element 20 for the purpose of securing the vessel V in place and clamping the gasket 22 between said frame elements to prevent the admission of water into the space enclosed by said element.

Provided for the man-hole 19 is a cover 25 having centrally therein a hole 26 which is bored to receive the stem 27 of screw which will hereinafter be designated as the king-screw. The stem of said king-screw is screw-threaded to receive a nut 28 above the man-hole cover and, below the latter, the king-screw is provided with an enlarged portion 29 which is also screw-threaded as indicated in Figs. 1 and 2. The stem 27, it is to be understood, fits the hole 26 of man-hole cover, but to prevent any leakage therethrough due to the pressure of the water in which the apparatus is submerged, I provide a taper to the shoulder 30 which serves as a valve with respect to a correspondingly shaped recess 31 provided in the under side of the cover when the shoulder is brought into said recess when the king-screw is raised.

32 represents a bridge-bar pivotally connected from near one of its ends to a bolt 33 extending downwardly from the partition 9. The free end of said bar is sustained by a hanger or support 34 which is offset below said partition to accommodate the bar and of a length sufficient to allow the bridge-bar to be swung from its full-line position (Fig. 3) into its dotted line position A to thereupon afford room for the passage of people through the man-hole.

The end 35 of said support serves as a stop to arrest the bar when it is swung into position diametrically of the man-hole and, to prevent the bar being accidentally retracted 5 from such stop, I provide a latch 36 to engage the bar from the side opposite the stop. Said bar is formed with a screw-threaded hole 37 which is engageable by the threaded lower end 29 of the king-screw when the 10 bar is located medially of the man-hole 12. The king-screw is provided at its upper end with an operating handle 38, and a socket-wrench 39 is provided for the heads of the various screws 23 and 50.

15 40 represents a plate for a man-hole 41 in the roof of the vessel and is desirably seated upon a combing or wall 43 which extends above said roof so that, when the vessel is floating and the plate 40 is removed, the combing prevents the waves or "wash" which may flow over the roof from entering the vessel. Openings, such as 44, are provided in the peripheral wall of the vessel for light or ventilating purposes and 25 may be glazed or otherwise, the same being protected by guard-plates 45 which are detachably connected to the wall of the vessel by screw-bolts 46 which are removable from the interior of the vessel.

30 Gage valves 47 or an equivalent, located above and below the height of openings 44, are used to determine when the vessel has reached the surface and if the openings 44 are exposed, to allow the removal of the 35 plates 45.

The operation of the invention is as follows: In preparing to leave the boat, the crew enter through opening 13 into compartment 10 and thence ascend through 40 man-holes 12 and 19 into the vessel V. Before the last person leaves the compartment, the door 14 is closed and secured by the screw-bolts 15, as shown in Fig. 2. When all hands are in the vessel the bridge-bar 32 is swung from its dotted line position A (Fig. 3) into the full line position whereat it is held by the latch 36, as illustrated in Fig. 4. The man-hole cover 25 with the king-screw therein is now placed 45 over the man-hole 19 and the cover then fastened down by screw-bolts 50. The king-screw is now rotated by its handle 38 to engage in the hole 37 of bar 32. By holding the handle of the king-screw to prevent 55 the latter turning and by screwing the nut 28 hard down against cover 25, it may be ascertained whether the king-screw is sufficiently engaged with the bridge-bar 32. When this is deemed satisfactory, the bolts 60 23 are successively unscrewed from their engagement in the holes 24 whereupon the king-screw alone serves to couple the vessel V to the boat. Consequently, to release the vessel the king-screw is turned to withdraw

screw-threads of the bar-hole 37. As this is accomplished the vessel ascends to the surface of the water. When the king-screw is disengaged from the bridge-bar 32 the former is raised to bring the shoulder 30 70 of the king-screw against the top of recess 31 to coact therewith to close the opening, if any, which may obtain about the king-screw in the hole 26 of the cover 25, and whereat it is secured by means of the nut 75 28 which is screwed down against the cover, as clearly shown in Fig. 2.

Various changes may be made from the aforescribed embodiment of the invention as, for example, the upper portion 16 of the 80 vessel may be more or less housed in a cavity provided in the deck, as indicated by 51 and 52, respectively, in Fig. 1.

What I claim as my invention, is—

1. In apparatus of the class described, a 85 floatative vessel provided with a man-hole in its bottom, a cover therefor, a king-screw extending through the cover, and means provided on a submarine boat for engaging the screw below said cover whereby the 90 vessel may be detached from the boat by operating the screw.

2. In apparatus of the class described, a floatative vessel provided with a man-hole in its bottom, a cover therefor, a king-screw 95 extending through the cover, a nut engaging the screw above said cover for regulating the king-screw when the same is inoperative, and means provided on a submarine boat for engaging the screw below 100 said cover whereby the vessel may be detached from the boat by operating the screw.

3. In apparatus of the class described, the combination with a boat having a well therein, a horizontal partition dividing said well and provided with a man-hole, and a bar extending across said man-hole and having a screw-threaded hole therein, of a floatative vessel provided with a man-hole in its 110 floor, a removable cover for the last named man-hole, screw-bolts for normally securing said vessel to the boat, a king-screw extending through said cover and engaging with the threads of said bar-hole for holding the vessel to said boat subsequent to the disengagement of said screw-bolts from the boat, and means interposed between the vessel and said partition to afford a non-leakable passageway between the aforesaid 115 man-holes.

4. In combination with a submarine boat having a well in its deck provided with a partition to afford a compartment therebelow, an opening provided with a door for 125 the admission of people into said compartment, a man-hole provided in said partition, a bar adjustably connected to said partition and extending across said man-hole,

bar, of a buoyant vessel provided with a man-hole in its floor, a cover for the last-named man-hole, a king-screw extending through said cover and engaging in said screw-threaded hole, frame elements respectively secured to the vessel and said partition between the latter, a packing between said elements, and screw-bolts operable from within said vessel and engaging the element which is secured to said partition for connecting the vessel to the partition.

Signed at Seattle, Washington, this 14th day of March, 1914.

CHRISTIAN W. FLINT.
